UNITED STATES PATENT OFFICE.

GEORGE W. LEWIS, OF LA SALLE, ASSIGNOR OF ONE-HALF TO CHARLES BRUNNER, OF PERU, ILLINOIS.

GAS OR VAPOR ENGINE.

SPECIFICATION forming part of Letters Patent No. 451,620, dated May 5, 1891.

Application filed March 4, 1890. Serial No. 342,582. (No model.)

To all whom it may concern:

Be it known that I, GEORGE W. LEWIS, of La Salle, in the county of La Salle and State of Illinois, have invented certain new and 5 useful Improvements in Gas or Vapor Engines; and I do hereby declare that the following is a full, clear, and exact description thereof, reference being had to the accompanying drawings, and to the letters of reference 10 marked thereon, which form a part of this specification.

This invention relates to the general class of machines known as "gas-engines."

It has among its objects to provide a construction adapted both for use of ordinary illuminating or other similar gas and for the use of vapor of petroleum or other volatile and inflammable vapor.

It also has among its objects to provide certain improvements in engines adapted to use petroleum or other vapor in connection with air to form the explosive compound.

The nature of the invention will be more fully understood from the following description of the accompanying drawings, which 25 illustrate one form of its embodiment.

In said drawings, Figure 1 is a top or plan view of the engine, showing the fly-wheel in horizontal axial section. Fig. 2 is a rear end 30 view of the machine. Fig. 3 is a central vertical section in the line 3 3 of Fig. 1, presenting the air-cylinder and the lever by which the pump and ignition-valve are operated in side elevation. Fig. 4 is a fragment of the 35 air-cylinder and its attached chamber in central vertical section or in the line 4 4 of Fig. 2. Fig. 5 is a horizontal section of the power-cylinder and its attachments in the line 5 5 of Fig. 2. Fig. 6 is a side elevation of the 40 oil or gas pump shown in connection with the pump-lever seen partly in central vertical section. Fig. 7 is a central vertical section in the line 7 7 of Fig. 6, including a fragment of the air-cylinder to which the oil or gas-pump 45 is shown attached. Fig. 8 is a central vertical section of the rear end of the power-cylinder and its attached ignition-chamber and induction-valve in the line 8 8 of Fig. 2. Fig. 9 is a detail in section on the line 9 9 of Fig. 50 3. Fig. 10 is an enlarged detail illustrating

the sliding cam-sleeve on the main shaft in connection with the lever which is operated by the cam thereon and which operates the oil-pump and ignition-valve.

A represents a bed or frame, B an air-pump 55 cylinder, and C a power-cylinder supported thereon parallel with each other.

D is a crank-shaft supported in pillow-blocks d d and carrying a fly-wheel D'. D² is a crank on one end of said shaft, connected 60 by the pitman c with the plunger C', that works in the power-cylinder C, and D³ is a crank on the opposite end of the shaft D, connected by the pitman b with the plunger B', that works within the air-pump cylinder B, 65 the crank-shaft D³ being set about thirty-six degrees in advance of the crank D². The shaft D is provided with a belt-pulley D⁴ for the transmission of power and with an eccentric d², Fig. 5, for operating the exhaust-valve of 70 the power-cylinder through the connecting-rods c'. On the shaft D is also mounted a sliding sleeve D⁵, having a cam d⁵, (seen in Figs. 1, 3, and 10,) which sleeve is splined or otherwise held from rotation on the shaft in 75 a familiar manner, and is slid thereon by the bent levers d⁸ of the centrifugal ball-governor illustrated in Fig. 1.

E is a lever operated by the cam on the sliding sleeve D⁵ for the actuation of an oil 80 or gas pump F and also for the reciprocation of the sliding valve G, through which the explosive compound is admitted to the ignition-chamber H of the power-cylinder C.

I is an open-ended pipe for the admission 85 of air to the air-cylinder B, and J a pipe by which the mingled air and gas or vapor is sent from the air-cylinder B to the ignition-chamber H of the power-cylinder. The pipe I is provided with a check-valve I', closing 90 outwardly from the chamber B², and the pipe J is provided at its extremity, where it connects with the power-cylinder, with a check-valve J', opening toward said power-cylinder. This check-valve J' is illustrated in detail in 95 Fig. 8, wherein the valve proper J² is shown suspended by a light but sufficient spring j from a pin j', extending across the upper end of the nipple, which forms the shell J' of the valve.

F' is a pipe leading from the pump F to the air-induction pipe I, and F² is a pipe by which the gas or the oil to be vaporized is delivered to the pump F from any suitable 5 source of supply. The pipe F² is provided with a check-valve F⁶, opening outwardly.

B² is a chamber applied to the rear end of the air-pump cylinder B and communicating with the interior of the latter through the perforated plate b'. The pipes I and J severally communicate with the chamber B², and both said pipes I and J, as well as the chamber B², are packed or filled with small wires, as illustrated in Figs. 4, 8, and 9, with a view to the 10 thorough subdivision and vaporization of the oil and the thorough commingling of the gas or vapor with the air on their passage to the ignition-chamber II of the power-cylinder.

The oil-pump F is illustrated in the details 20 of its construction in Figs. 6 and 7. It consists of a shell F³, which, as illustrated in the drawings, is provided with a laterally-projecting screw-threaded stud f entering a boss b², which projects from the side of the air-cylinder B near its rear or receiving end. The shell F³ is vertical, and has in its lower portion a longitudinal cylindric space f', forming a valve-chamber, into which leads the pipe F². From the valve-chamber f' leads the 25 smaller longitudinal passage f², which continues upwardly through the top of the shell, and from the sides of the shell opposite the lower portion of the passage f² projects a nipple f³. This nipple is chambered to receive the valve F⁴, seated at the inner end of the 30 chamber, as shown in Fig. 7, by a spring f⁴, and, when seated, closing the small outlet-orifice f⁵, which leads from the passage f². To the nipple f³ is attached the pipe F', which 35 leads to the air-induction pipe I. Within the chamber f' of the valve-shell F³ is fitted a valve F⁵, constructed to afford passage of liquid from below to above it by marginal notches, as shown in Fig. 7, or otherwise in 40 any suitable manner. Beneath this valve F⁵ is placed an expanding spring f⁶, which normally forces the valve F⁵ upward and against its seat at the upper end of the valve-chamber f', cutting off its communication with the 45 passage f². The valve F⁵ is provided with an upwardly-extended stem f⁷, which occupies the passage f² and protrudes through a stuffing-box f⁸ at the top of the shell, passing through a slot or opening e in the lever E. Said stem is reduced in its lower portion 50 above its head, forming the valve F⁵, as indicated in Fig. 7, so that when the valve and its stem are depressed the valve-chamber f' communicates with the orifice f⁵. The lever E is provided with a tappet E', 55 projecting over the upper end of the valve-stem f⁷, so that when the lever E is vibrated by the cam on the sleeve D⁵ and its end adjacent to the pump F is depressed said tappet will strike the upper end of the valve-stem f⁷ and force the valve and its stem downwardly in its chamber f'. In this operation

the oil occupying said chamber beneath the valve F⁵ passes the valve F⁵ and is forced by displacement through the orifice f⁵. When 70 the lever E is lifted, the spring f⁶ raises the valve F⁵ against its seat and prevents the passage of more oil or gas through the pump before the next downstroke of the lever E.

The tappet E' is made adjustable for the 75 purpose of permitting a variation of the stroke of the valve F⁵ and a corresponding variation of the quantity of oil forced thereby into the air-induction pipe in connection with a uniform movement of the lever E. As a 80c desirable construction by which adjustment of the tappet E' may be made, said tappet is illustrated in Fig. 6 as consisting of a bent plate, one arm—to wit, that which strikes the valve-stem f⁷—being substantially parallel 85 with the lever E and its other arm e' bent at right angles with such parallel portion and passing through an opening e² in the lever E, or otherwise engaged with said lever to prevent its turning. Through the parallel portion of the tappet passes a stud e³, which is affixed to the lever E, and is provided above the tappet with a thumb-screw E⁴. Between the tappet and the lever and surrounding this stud is inserted an expanding coiled spring 90 e⁵, operating to hold the tappet firmly against the under surface of the thumb-screw in any adjustment of the latter. By means of the thumb-screw and spring the tappet E' may manifestly be raised or lowered to any extent 95 desired, so as to give a corresponding extent of downthrow to the valve F⁵ in its chamber f'.

The means shown for igniting the mingled 100 gas or vapor and air in the ignition-chamber II is the generally familiar one of a tube K, closed at its outer end, but having communication through a valved passage h with the interior of the ignition-chamber and subjected to the heating action of a flame applied to its external portion.

K' is a chimney or lateral inclosure embracing a portion of the tube K and open at its top and bottom to confine the heat of a gas or lamp flame arranged to heat the tube 115 K within such inclosure to a sufficiently high degree to ignite the explosive compound entering the same from the ignition-chamber.

The valve G, by which communication is 120 opened and closed between the interior of the tube K and the ignition-chamber II, is a flat plate embraced within a frame g, having a rectangular opening g' of suitable size to confine the valve G at its upper and lower edges, but to allow of suitable horizontal movement 125 of said valve to permit the latter to cover and uncover the inner and open end of the tube K. This frame g is embraced between the outer plane surface of the head h' of the chamber II and an external plate h², into which the tube K is screwed at its inner and open end. Against the inner face of the valve G bears a thin plate g³ of the full size 130 of the valve-chamber g', having an opening

which registers with the passage h^1 . Back of this plate g^2 is a recess in the head h' , containing an expanding spring h^5 , tending to keep the plate g^2 in constant bearing against the valve G . Through the outer head h^2 is a passage h^6 , communicating with the outer air, and the outer surface of the valve G is provided with a longitudinal groove g^3 , which registers with the opening h^6 and with the opening of the tube K , so that after the valve has closed the tube K from communication with the ignition-chamber said tube is opened to the outer air through said groove g^3 and the passage h^6 . For the operation of the valve G the head h^2 is provided with a horizontal slot h^7 , through which projects a pin or stud g^4 , having a head at its outer end. With the pin g^4 connects the pitman or rod L , to the side of which, as best seen in Fig. 1, is fastened the end of a spring l , the free end of which embraces the pin g^4 beneath its head, with a tendency to draw the valve G into close contact with the plate h^2 .

By the construction above described the valve G , notwithstanding it is subject to wide changes of temperature, is always free to act, while it is also always tight or close without the aid of objectionable packing. By means of the groove g^3 of said valve and the passage h^6 , leading from the valve-chamber to the outer air, the pressure is taken off the tube K at each throw of the valve, with the advantages of enabling a shorter tube to be used than would otherwise be necessary, of securing freer and more uniform action of the valve, and of permitting more ready admission of fresh explosive compound to the tube preparatory to ignition.

The ignition-valve G is operated by the same lever E which operates the pump F . To this end the rod L , which is connected with the valve G , is at its opposite end connected with an arm L' on a rock-shaft L^2 . (Shown more plainly in Fig. 2.) Said shaft opposite the end of the lever E is provided with a second and horizontal arm L^3 , to the end of which is pivoted a rod l' , which extends upward into flexible connection with the lever E , as illustrated in Fig. 6, or otherwise in any suitable manner. The vibration of the lever E therefore operates both the ignition-valve G and the pump F , while the adjustable tappet E' permits the stroke of the pump to be varied without varying the motion of the valve G .

The exhaust-port c^2 of the power-cylinder C is located at the side of the cylinder, as shown in Fig. 5, and communicates with a valve-chamber C^2 , similar to the valve-chamber g' , containing the valve G , and through it with the exhaust-pipe M . In said pipe M is connected a chamber or box M' , which, with the portion m of the exhaust-pipe M beyond the box, is filled with wire or other loose packing. The effect of the chamber M' and such packing is to prevent objectionable noise from the exhaust while allowing free escape of the partially-expanded gas into the open

air. The sliding exhaust-valve M^2 is provided with a stud m' , which projects through a slot m^2 in the cap-plate of the valve-chest, and to this stud is pivoted the extremity of the eccentric-rod c' .

Next describing the manner in which the lever E is controlled by the action of the cam d^5 on the sliding cam-sleeve D^5 , I first point out that said sleeve is provided with a flange d^4 , having an annular groove, as illustrated in Figs. 1 and 10, for the engagement therewith of the arms d^3 of the centrifugal governor. The cam d^5 (seen in outline in Fig. 3) extends from the flange d^4 only part way to the extremity of the sleeve, as illustrated in Fig. 10. The lever E projects over the sleeve D^5 and is extended beyond the sleeve and downwardly and backwardly beneath it, as illustrated in Fig. 3, the backwardly-bent end being marked e^6 . At a point directly above the cam-sleeve the lever E is provided with a friction-roller e^7 , intended to strike and ride the cam d^5 when the sleeve is in proper position for that purpose. The backwardly-bent end e^6 of the lever is out of line with the roller e^7 , as shown in Fig. 10, so that, while the sleeve may be moved so as to carry the cam out of engagement with the roller, said backwardly-turned extremity e^6 of the lever is always in position to be engaged by said cam.

In the construction described, when the speed of the engine is such as to require the admission and expansion of the explosive to and within the power-cylinder, both the roller e^7 and the end e^6 of the lever E will be alternately engaged by the cam d^5 , the latter acting when it strikes the roller to depress the remote end of the lever E and to force downward the valve F^5 of the oil-pump valve and to also throw open the ignition-valve G . Upon the further revolution of the cam d^5 the latter strikes the end e^6 of the lever E and raises the remote end thereof, allowing the valve F^5 to rise under the impulse of the spring f^6 and acting through the rock-shaft L^2 and its connections to close the valve G . When, however, the speed of the engine is increased to its predetermined maximum velocity, the governor through its arms d^3 draws the sleeve D^5 inward toward the hub of the fly-wheel D' , and in doing this moves the cam d^5 out of the path of the roller e^7 while it is still in position to engage the extension e^6 of said lever. The action of the cam d^5 in this position of the sliding sleeve is to keep the remote end of the lever E raised and to hold the ignition-valve G closed, while also preventing operation of the oil-pump F . As in other engines of this class, this suspension of supply to the power-cylinder continues until the speed of the engine is so far reduced as to carry the sleeve D^5 outward far enough for its cam d^5 to again engage the friction-roller e^7 on the lever E , whereupon said lever is again vibrated and the oil-pump and ignition-valve are both again put in operation.

As a desirable construction, the pipe F' de-

livers into the air-induction pipe I through a nozzle f^a , extending to the middle of the pipe I, and provided with a reduced orifice for discharge of the oil, as illustrated in Fig. 9.

- 5 The oil-pump described is equally adapted for use with gas or oil, and when it is desired to use ordinary gas instead of vapor to supply the air with the inflammable or explosive quality necessary to the operation of 10 the engine the pipe F^2 will be attached to a source of gas-supply and the pump F will be operated precisely as though oil-vapor were employed.

15 The advantage of the pump in the use of gas is that it definitely controls the valve F^5 when elevated against its seat, effectively closing off the admission of gas or oil and limiting the amount available for the explosive 20 action to that already admitted to the ignition-chamber through the connections I J.

I claim as my invention—

1. In an engine of the general character described, the combination, with the air-pump, of an oil-pump F, having the passages f' and f^2 , of unequal diameters, and the passage f^5 , leading from the smaller passage f^2 , a valve F^5 , constructed to seat at the upper end of the larger passage f' and provided with a stem f^7 , protruding through the shell, a spring 30 applied to press the valve F^5 against its seat, a spring-valve F^4 , applied to the orifice f^5 , and means for intermittently forcing the valve F^5 from its seat subject to control according to the speed of the engine, substantially as described.

2. In an engine of the general character described, the combination, with a pump for oil or gas, of a pivoted lever E, a sliding sleeve D on the engine-shaft, subject as to its position to the action of the engine-governor, the lever E, extending both above and below the cam-sleeve and having the parts on opposite sides of said sleeve in different planes, whereby when the sleeve is so far retracted as to bring its cam out of engagement with the lever for the operation of the pump it will be held by the cam from operating the pump, substantially as described.

3. In an engine of the general character described, the combination, with the power-cylinder and the air-pump cylinder, of an ignition-valve connected with the power-cylinder and an oil or gas pump connected with the air-pump cylinder, a sliding cam-sleeve on the engine-shaft controlled by the engine-governor, and a lever adapted to engage with the cam of said sleeve and having operative connection with both the oil-pump and the ignition-valve, substantially as described.

4. In an engine of the general character described, the combination, with an air-pump, a power-cylinder, and their connecting-passages, of a pump for gas or oil, a valve for admitting the explosive compound to the power-cylinder, and a single lever for operating the oil or gas pump and the ignition-valve, which lever is provided with means for imparting a variable throw to the oil-pump while giving a uniform throw to the valve.

5. In an engine of the general character described, the combination, with the ignition-valve and with an oil or gas pump, of a vibrating lever actuated from the main shaft and having operative connection with said ignition-valve and with said oil or gas pump, the connection with said oil or gas pump being adjustable, whereby the movement of the movable parts of the pump may be varied while the movement of the ignition-valve remains uniform, substantially as described.

6. In an engine of the general character described, the combination, with an oil or gas pump, as F, in which the piston is thrown in one direction by a spring, of a vibrating lever E for operating the oil-pump, a cam upon the main shaft actuating the lever, and an adjustable tappet, as E', on the lever for engagement with the moving parts of said oil-pump, substantially as described.

In testimony that I claim the foregoing as my invention I affix my signature in presence of two witnesses.

GEORGE W. LEWIS.
